W. B. ACKER.
TREAD FOR BOOTS AND SHOES.
APPLICATION FILED MAR. 27, 1911.

1,003,576.

Patented Sept. 19, 1911.

UNITED STATES PATENT OFFICE.

WILLIAM BERTRAND ACKER, OF WASHINGTON, DISTRICT OF COLUMBIA.

TREAD FOR BOOTS AND SHOES.

1,003,576.

Specification of Letters Patent. Patented Sept. 19, 1911.

Application filed March 27, 1911. Serial No. 617,192.

To all whom it may concern:

Be it known that I, WILLIAM BERTRAND ACKER, a citizen of the United States, residing at Washington, in the District of Columbia, have invented certain new and useful Improvements in Treads for Boots and Shoes; and I do hereby declare the following to be a full, clear, and exact description of the invention, such as will enable others skilled in the art to which it appertains to make and use the same, reference being had to the accompanying drawings, and to reference characters marked thereon, which form a part of this specification.

This invention relates to treads for attachment to the heels of boots, shoes, and other footwear.

Heretofore, in the manufacture of treads, it has been proposed to embed a plug of wear resisting material, such as leather or fabric in the lower surface of the tread in order to prevent slipping of the heel when walking and excessive wear on the material constituting the body of the tread. Such a construction has been found objectionable in actual practice, in that the constant pounding on the heel of the shoe incident to walking soon causes the exposed portion of the plug to wear in the direction of the outer edge of the heel and present an inclined surface to the ground, with the result that the plug instead of acting as an anti-slipping device, enhances the tendency of the heel to slip or slide, especially when walking on smooth or wet surfaces. It has also been proposed to provide the heel of a shoe with a series of strips of fabric standing on edge and slantingly disposed with relation to the tread in order to insure a good anti-slipping surface. These fabric strips, however, extend approximately the entire length and width of the heel so that while the anti-slipping qualities of the heel are in a measure increased, yet such a heel does not meet the conditions of service in that the fabric strips are not concentrated at the outer portion of the heel, and furthermore, where the heel is made of rubber or other yieldable material, the resilient or elastic property of the rubber is either totally or partially destroyed.

The primary object of the present invention is to obviate the objectionable features referred to and to present to the trade a heel or tread of simple and durable construction

having a plurality of longitudinal wear resisting strips embedded therein so as to prevent slipping when walking on smooth or wet pavements, the invention being particularly adapted for use with cushion heels or treads, as the strips do not impair the elastic or resilient properties thereof.

A further object of the invention is to provide a heel or tread, the construction of which is such as to present an anti-slipping surface of constantly increasing area proportionate to the amount of wear on said heel or tread.

A further object is to provide a tread having a plurality of converging wear resisting strips embedded therein and terminating short of the breast of the heel, thus to present a composite tread surface having different degrees of elasticity in the length thereof.

A still further object of the invention is generally to improve this class of devices so as to increase their utility, durability and efficiency, as well as to reduce the cost of manufacture.

Further objects and advantages will appear in the following description, it being understood that various changes in form, proportions, and minor details of construction may be resorted to within the scope of the appended claims.

For a full understanding of the invention reference is to be had to the following description and accompanying drawing, in which;

Figure 1 is a perspective view of a shoe provided with a tread constructed in accordance with my invention; Fig. 2 is an inverted perspective view of the tread detached; Fig. 3 is a vertical sectional view taken on the line 3—3 of Fig. 1, looking in the direction of the arrow; Fig. 4 is a transverse sectional view taken on the line 4—4 of Fig. 2, and looking in the direction of the arrow, the position of the tread being reversed or in normal position; Fig. 5 is a similar view showing a modified form of the invention; Fig. 6 is a perspective view looking at the upper face of the tread showing a further modification; Fig. 7 is a similar view showing a still further modification.

Corresponding and like parts are referred to in the following description and indicated in all the views of the accompanying drawing by the same reference characters.

The tread forming the subject matter of the present invention is principally designed for attachment to the heels of boots, shoes, and other footwear, and by way of illustration is shown applied to a shoe of the ordinary construction, in which 5 designates the vamp, 6 the sole and 7 the heel.

The tread comprises preferably a yieldable body portion 8 formed of rubber or other suitable material adapted to be attached to the lower lift of the heel 7, as best illustrated in Fig. 1 of the drawing. Embedded in the rubber or other material constituting the body portion 8 are a plurality of spaced longitudinal strips of wear resisting material 9, said strips converging longitudinally in the direction of the rear end of the body portion, and downwardly in the direction of the tread surface thereof so as to present a good anti-slipping surface to the ground and also to concentrate the exposed edges of the strips at that portion of the heel subjected to the most wear. The strips 9 are preferably corrugated at 10 to assist in anchoring the strips within the body portion and also to reinforce and strengthen the same. The lower longitudinal edges of the strips 9 are preferably cut away from a point approximately at the center of the tread to the inner ends of the strips, as indicated at 11, while the lower longitudinal edges of the strips between the cut away portions 11 and the rear end of the tread are exposed so as to present in effect a composite heel, the forward or breast portion 12 of which constitutes a yieldable surface, and the rear portion thereof an anti-slipping surface. The tread may be attached to the heel 7 of the shoe in any suitable manner, as by nails, or similar fastening devices 13, there being suitable openings 14, preferably formed in the tread to permit the passage of the fastening devices, as shown.

It will here be noted that by converging the wear resisting strips 9 both vertically and longitudinally, an increasing anti-slipping surface is presented to the ground proportionate to the amount of wear on the heel, as clearly shown in Fig. 4 of the drawing. Thus it will be seen that as the rear end of the tread wears away in the act of walking an anti-slipping surface of constantly increasing area will be presented to the ground, said anti-slipping surface consisting of alternate layers of yieldable material and wear resisting material so as effectively to prevent slipping or sliding of the heel, especially when walking on smooth surfaces such as ice, wet pavements, and the like. It will also be seen that by having the rear ends of the wear resisting strips exposed, and the forward ends thereof entirely embedded within the body of the tread, the forward or breast portion of the tread will allow sufficient resiliency of the heel to re-

ceive and absorb the jar or shock incident to walking.

If desired the elastic tread 8 may be made of the same height and width as the heel 7 and used in place of the ordinary leather or rubber heel, that is to say the body portion 8 instead of being used as a tread may be used as the heel itself. I therefore desire it to be understood that by the term "tread" I mean either the lower lift of the heel or sole of a shoe, or the heel or sole itself. I also desire it to be understood that the body of the tread need not necessarily be formed of rubber or other yieldable material, as the wear resisting strips 9 may be embedded in or applied to an ordinary leather heel or sole with good results.

In some cases the strips of wear resisting material 10 instead of being corrugated may be provided with oppositely disposed plane surfaces, as indicated at 15 in Fig. 5 of the drawing, the construction and operation of the device being otherwise the same as that shown in Fig. 1.

In Fig. 6 of the drawing there is illustrated a modified form of the invention in which the strips of wear resisting material 9' extend from the opposite longitudinal edges of the body portion and intersect a line drawn approximately through the center of said body portion, so as to concentrate the wear resisting strips at the rear end of the heel.

In Fig. 7 of the drawing the position of the strips is reversed, that is to say the strips converge in the direction of the breast of the heel and terminate short thereof, as indicated at 16, although these strips may be extended the entire length of the heel if desired without departing from the spirit of the invention.

It will of course be understood that the strips 9 may be made of fabric, vegetable fiber, leather, metal or other suitable material possessing the requisite degree of toughness to resist excessive wear on the heel. It will also be understood that the wear resisting strips may be molded or otherwise embedded in the body of the tread during the manufacture thereof, or suitable kerfs may be formed in the body of the tread and the wear resisting strips inserted therein, and the several parts cemented, vulcanized, or otherwise treated to hold said strips in place without departing from the spirit of the invention.

Having thus described my invention, what I claim as new is:—

1. A tread having spaced longitudinal strips of wear resisting material embedded therein and converging downwardly toward each other in the direction of the tread surface, said strips extending from the rear portion of the tread forwardly toward the breast thereof.

2. A tread including a yieldable body portion having spaced strips of wear resisting material embedded therein and converging longitudinally in the direction of the rear end of said body portion and downwardly in the direction of the tread surface thereof.
3. A tread having spaced strips of wear resisting material embedded therein and converging downwardly toward each other in the direction of the tread surface thereof, said strips being exposed at the tread surface for a portion only of the length of said strips.
4. A tread having spaced wear resisting strips embedded therein with a portion of their lower longitudinal edges spaced from the tread surface at the inner end thereof and substantially flush with said tread surface at the outer end thereof.
5. A tread having spaced strips of wear resisting material embedded therein and converging both vertically and longitudinally of said tread.
6. An elastic tread having spaced strips embedded therein and extending approximately the entire length of the tread, the lower longitudinal edges of the strips being cut away so as to present a yieldable surface at the inner end of the tread and an anti-slipping surface at the outer end of said tread.
7. An elastic tread including a yieldable body portion having spaced longitudinal strips of wear resisting material embedded therein and converging longitudinally in the direction of the outer end of the body portion and downwardly in the direction of the tread surface thereof, the lower longitudinal edges of the strips at the inner end of the body portion being cut away and spaced from the tread surface thereof.
8. An elastic tread including a yieldable body portion having converging wear resisting strips embedded therein and concentrated at the outer end of the body portion, the inner end of the body portion at the tread thereof presenting an elastic surface to the ground.
9. A tread having spaced corrugated strips of wear resisting material embedded therein and converging both vertically and longitudinally of the tread, thereby to present an increasing anti-slipping surface proportionate to the amount of wear thereon.
10. A cushion heel comprising alternate strips of yieldable material and wear resisting material, said strips of wear resisting material converging longitudinally in the direction of the outer end of the heel and downwardly in the direction of the tread surface thereof.
11. An elastic tread including a yieldable body portion having converging wear resisting strips embedded therein and concentrated at the outer end of said body portion.
12. A tread including a body portion having spaced strips of wear resisting material embedded therein and converging both vertically and longitudinally of the tread, said strips being concentrated at the outer end of said body portion.
- In testimony whereof I have signed my name to this specification in the presence of two subscribing witnesses.
